UNITED STATES PATENT OFFICE.

FRANK B. WAGNER, OF CLEVELAND, OHIO.

DESIGN FOR A COIN-HOLDER CASE.

SPECIFICATION forming part of Design No. 26,637, dated February 16, 1897.

Application filed September 23, 1896. Serial No. 606,789. Term of patent 7 years.

To all whom it may concern:

Be it known that I, FRANK B. WAGNER, a citizen of the United States, and a resident of Cleveland, county of Cuyahoga, and State of Ohio, have invented and produced a new and original Design for a Coin-Holder Case, of which the following is a specification, reference being had to the accompanying drawings, forming part thereof, and which represent views of a coin-holder case embodying my design.

Figure I is a front elevation of my coin-holder case, showing my design. Fig. II is a top view of the same, and Fig. III a rear elevation, these three views being deemed necessary to fully illustrate my design.

The shape and configuration of my design are as follows:

The coin-holder consists of the series of cylindrical barrels inclosed in a casing A, generally conforming with the outline of the series of barrels and surmounted by the scalloped plate a.

The front of the casing has affixed thereto the advertising-frame C, of substantially the height of the casing A and of less width than the width of said casing, and is centrally located thereon, whereby the casing projects equally from each side of the frame. On each side and near the top of the casing is affixed a U-shaped eye D, whereby the coin-

holder is depended. The rear of the casing has centrally located thereon the flat coin-receptacle B, of less width than the width of the casing, and is formed with a contracted neck and an outwardly and upwardly flaring mouth b, which projects above the top of the casing. Clips E are transversely attached, one near the top and one near the bottom of the receptacle B.

What I distinctly point out and desire to claim as my invention is—

The herein-described design for a coin-holder, consisting of the barrel-casing having a flattop and base and rounded ends, the front of said casing having a rectangular frame centrally located thereon, the rear of said casing having the receptacle projecting therefrom and also projecting upwardly above said casing, said receptacle having the contracted neck and the flaring mouth, the U-shaped eyes on the side of said casing and the clips on the back of said receptacle, substantially as set forth.

In testimony that I claim the foregoing to be my invention I have hereunto set my hand this 22d day of September, A. D. 1896.

FRANK B. WAGNER.
